UNITED STATES PATENT OFFICE.

EDWARD M. BARNES, OF HASTINGS, MICHIGAN, ASSIGNOR TO AMERICAN UTILITIES COMPANY, OF ST. JOSEPH, MICHIGAN.

ELECTRIC WATER-PURIFIER.

1,267,044.

Specification of Letters Patent. Patented May 21, 1918.

Application filed June 30, 1917. Serial No. 177,956.

To all whom it may concern:

Be it known that I, EDWARD M. BARNES, a citizen of the United States, residing at Hastings, county of Barry, State of Michigan, have invented certain new and useful Improvements in Electric Water-Purifiers, of which the following is a specification.

This invention relates to electric water purifiers.

10 The objects of this invention are:

First, to provide an electric water purifier of that type in which spaced electrodes are immersed in the water to be purified, that is simple in structure, economical to manufacture and easily maintained in a sanitary condition.

Second, to provide a purifier of the class described, which comprises a receptacle for holding the water being purified provided

20 with a detachable cover in which the electrode support is removably mounted so that it may be easily removed for the purpose of removing the coating from the electrodes which is deposited thereon during the operation of the device.

25 Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing, forming a part of this specification, in which:

Figure I is a vertical sectional view through my improved purifier, the electrode holder being shown in side elevation.

40 Fig. II is a side elevation of my improved electrode holder.

Fig. III is a detail central longitudinal section therethrough.

Fig. IV is a transverse section taken on a 45 line corresponding to line 4—4 of Fig. II.

Fig. V is a transverse section taken on a line corresponding to line 5—5 of Fig. III.

Fig. VI is a detail longitudinal section taken on the broken line 6—6 of Fig. III.

50 Fig. VII is a detail longitudinal section of a modified embodiment of my improved electrode holder.

Fig. VIII is a plan view of the cover for the water container.

Fig. IX is a plan view of the container 55 with cover removed.

In the drawing, similar reference characters refer to similar parts throughout the several views, and the sectional views are taken looking in the direction of the little 60 arrows at the ends of the section lines.

Referring to the drawing, the reference character 1 indicates my improved electrode holder as a whole. This holder comprises the cylindrical body member 2 which is provided with a central longitudinal slot 3, the sides of which have the channels or grooves 4 formed therein for receiving the bar electrodes 5. The lower end of the slot 3 is provided with recesses 6 for the lower ends of 70 the electrodes.

A pair of rectangular openings 7 in the upper end of the body member form continuations of the grooves 4 for receiving the upper ends of the electrodes 5 and form between them the spacing block 8 which holds the upper ends of the electrodes in spaced relation. The upper ends of the electrodes are provided with laterally extending lugs 9 which rest upon the upper end of the body 80 member. The upper end of the body member is screw threaded at 10 to receive the cap 12 internally threaded at 11. The cap is provided with a shoulder 13 which engages the lugs 9 and clamps them onto the 85 upper end of the body member.

The upper ends of the electrodes are provided with binding screws 14 for the terminals 15 of the conductors 16. The conductors 16 are supported and protected by a protector of well known design comprising an insulating bushing 17, to which the upper end of the coiled spring 18 is secured. The lower end of the coiled spring is threaded into the upper end of the cap 12. 95

In the modification disclosed in Fig. VII, instead of providing the electrodes with lugs which project from the edges thereof, the upper ends of the electrodes are bent at right angles thereto, forming the lugs 9' 100 which rest upon the upper end of the body member and are secured thereto by means of the cap 12. The terminals 15' are secured to the laterally extending lugs 9'.

The body member and cap may be made of any suitable insulating material, but I preferably make these members of hard rubber, porcelain, glass, or any other material which can be easily molded. The electrodes are preferably formed of aluminum or aluminum alloy, or graphitic carbon.

The container 20, which is preferably glass, is provided with a faucet 21, suitable gaskets 22 being provided to prevent leaking. The faucet 21 is disposed above the receptacle bottom, so that the purified water may be decanted off from above the precipitated matter in the bottom of the container. The open upper end of the container 20 is provided with a shoulder 23 upon which rests a gasket 24. The cover 25, which may be constructed of glass, porcelain, hard rubber, or any other suitable insulating material, is provided with a flat central boss 26 having an aperture 27 which is larger in diameter than the body member 2. The outer periphery of the cover 25 is provided with a downturned flange 28 which rests upon the gasket 24, and an upwardly projecting annular head or rib 29. Clips 30 engage the rib 29 and the lower side of the shoulder 23 to hold the cover 25 in place.

In use the cylindrical electrode holder is inserted through the aperture 27 with its cap 12 resting upon the boss 26. When current is supplied to the electrodes through the conductors 16, the matter in suspension in the water will be first coagulated and then precipitated and the water sterilized.

After my purifier has been in use for some time, deposits form upon the surfaces of the electrodes and it becomes necessary, therefore, to remove these deposits. The electrode holder may be freely removed from the container. To make the surface of the electrodes accessible for cleaning, the depth of the groove 4 is made less than the thickness of the electrodes 5, so that the outer surfaces of the electrodes project beyond the outer surfaces of the walls of the slot 3, as shown in Figs. II and IV. The faces of the electrodes may be quickly cleaned by passing a cloth or a scraping implement through the slot 3. When the outer surfaces of the electrodes become worn, the electrodes may be reversed in the grooves 4.

Having thus described my invention, what I claim as new and desire to secure by Letters Patent, is:

1. In a structure of the class described, the combination of a cylindrical body member of insulating material having a central longitudinal slot therein and opposed internal longitudinal electrode receiving grooves in the side walls of said slot and recesses at the lower ends of said grooves and openings through the upper end of said body alined with said grooves, electrodes having later-

ally projecting lugs at their upper ends disposed in said grooves and their upper ends projecting through said openings and their said lugs resting on the upper end of said body, an internally shouldered cap having a conductor opening in the top thereof threaded upon said body with its shoulder engaging said lugs, said electrodes being provided with binding screws, and a conductor protector secured in said conductor opening of said cap.

2. In a structure of the class described, the combination of a cylindrical body member of insulating material having a central longitudinal slot therein and opposed internal longitudinal electrode receiving grooves in the side walls of said slot and openings through the upper end of said body alined with said grooves, electrodes having laterally projecting lugs at their upper ends disposed in said grooves and their upper ends projecting through said openings and their said lugs resting on the upper end of said body, an internally shouldered cap having a conductor opening therein threaded upon said body with its shoulder engaging said lugs.

3. In a structure of the class described, the combination of a body member of insulating material having a central longitudinal slot therein and opposed internal longitudinal electrode receiving grooves in the side walls of said slot and openings through the upper end of said body alined with said grooves, electrodes disposed in said grooves with their upper ends projecting through said openings, a cap having a conductor opening therein inclosing the upper ends of said electrodes and the conductor connections thereto.

4. In a structure of the class described, the combination of a molded slotted body member, the upper end wall of which is provided with a pair of spaced apertures, a pair of electrodes inserted through said apertures and extending along the opposite walls of said slot, the upper ends of said electrodes being provided with lateral lugs resting upon the upper end of said body member, means for securing the terminals of electrical conductors to the upper ends of said electrodes, and a cap detachably connected to the upper end of said body member surrounding said terminal securing means and clamping said lateral lugs to said body member.

5. In a structure of the class described, the combination with a slotted body member of insulating material, the wall of the slot having electrode grooves therein, of a pair of electrodes mounted in said grooves, means for securing the terminals of electric conductors to said electrodes, and a cap surrounding said terminal securing means, the

said electrodes and cap being provided with coacting means for securing said electrodes to said body member.

6. In a structure of the class described, the combination of a longitudinally slotted body member of insulating material, the walls of the slot having electrode grooves therein, electrodes arranged in said grooves with their faces projecting therefrom and their upper ends projecting from the slot at the upper end of the body and being removable therefrom, means for retaining said

electrodes engaging their projecting ends and means for securing the terminals of electric conductors to the projecting ends of said electrodes.

In witness whereof, I have hereunto set my hand and seal in the presence of two witnesses.

EDWARD M. BARNES. [L.S.]
